(57) CLAIM

The ornamental design for a cap for body care product, as shown and described.

DESCRIPTION

FIG. 1 is a front perspective view of a cap for body care product, according to an embodiment;

FIG. 2 is a front view of the cap for body care product illustrated in FIG. 1;

FIG. 3 is a rear view of the cap for body care product illustrated in FIG. 1;

FIG. 4 is a left side view of the cap for body care product illustrated in FIG. 1;

FIG. 5 is a right side view of the cap for body care product illustrated in FIG. 1;

FIG. 6 is a top view of the cap for body care product illustrated in FIG. 1;

FIG. 7 is a bottom view of the cap for body care product illustrated in FIG. 1;

FIG. 8 is a bottom perspective view of the cap for body care product illustrated in FIG. 1; and,

FIG. 9 is a rear perspective view of the cap for body care product of FIG. 1, shown in an environment of use.

The broken lines illustrate portions of the cap for body care product forming no part of the claimed design. In FIG. 9, the additional broken line showing of a container illustrates environmental subject matter and forms no part of the claimed design.
